MOUNTING FOR A DOMESTIC WASH WRINGER

Arthur Henry Freeman, London, England, assignor to The International Nickel Company, Inc., New York, N. Y., a corporation of Delaware

Application January 21, 1939, Serial No. 252,136
In Great Britain March 9, 1938

5 Claims. (Cl. 68—239)

The present invention relates to a mounting for a domestic wringer, and more particularly to a wringer mounting which allows the wringer to be placed in an operative position above a drainboard, or sink, or the like, and to be moved into an inoperative position below the same without detaching the wringer from its mounting.

Many modern houses and apartments have been constructed without providing a space in which a washing machine and wringer may be used, or stored when not in use. In almost all homes, however, it is convenient if not necessary to do a certain amount of washing. The kitchen sink is thus often called into service as a washing tub. My invention provides a convenient mounting for a wringer adjacent to a sink or similar fixture which permits the wringer without detachment from the mounting to be readily placed in operative position above the plane of the sink during use and to be moved to a storage position below the sink when not in use.

It is an object of my invention to provide a mounting for a domestic wringer which permits the wringer mounted thereon to be swung into operative position above a sink and to a storage position below the same.

A further object of my invention is the provision of a mounting for domestic wringers of simple yet sturdy construction which can be manufactured and installed on existing equipment at relatively small cost.

Other objects and advantages of the present invention will be apparent from the following description, taken in conjunction with the drawing, in which—

Fig. 1 is a fragmentary front elevation of a sink with the wringer mounting attached and in operative position, the wringer having parts broken away; and

Fig. 2 is a vertical section on the line 2—2 of Fig. 1, the mounting in storage position being indicated by broken lines.

Generally speaking, the invention provides a mounting for a wringer which can be swung from an operative position above a draining board or sink about an axis normal to the longitudinal vertical plane through the wringer to an inoperative or storage position below the board or sink. Preferably the wringer is arranged to swing through an angle of approximately 270° and the pivot of the mounting may conveniently be arranged below and slightly inside the edge of the board. Means are prefer-

ably provided to secure the wringer in both its operative and inoperative position.

The invention is particularly applicable to cases where it is desired that the wringer, when in its operative position, should be between a draining board and a sink. For example, when used with a sink fixed against a wall and provided with a draining board on one side, the wringer, when in its operative position, is arranged at right angles to the wall near the edge of the board which adjoins the sink. The mounting is especially suitable for use with metal sink and draining board combined units.

Referring now more particularly to the drawing, the wringer 1 is shown in its operative position mounted on a metal sink and draining board unit consisting of two sinks 5a and 5b connected by a draining board 4. The wringer is carried by a mounting which consists of a pivoted wringer supporting member 2 and a fixed bracket 7. One relatively long arm 2a of the supporting member 2 carries sockets 3a which grip the wringer spigots 3 by means of set-screws 3b. The supporting member 2 comprises two further relatively short arms 2b and 2c, which, in the operative position, embrace the edge of the board 4, as may be seen in Fig. 2. The arms 2a and 2c may be made of sheet metal doubled on itself and may be welded or otherwise secured in generally parallel relation to each other to the tubular connecting arm 2b. The sockets 3a are similarly welded or otherwise secured to the arm 2a.

The bracket 7 is secured to the underside of the draining board 4 in any suitable manner. It may conveniently take the form of an inverted channel having the rear end welded or otherwise secured to a wall plate 8. A pivot pin 6 extending through aligned bearing openings in the two vertical walls of the bracket 7 and in the short arm 2c pivotally secures the supporting member 2 to the bracket 7. When the wringer is moved into its inoperative position, the supporting member 2 together with the wringer is swung bodily about the pin 6 through an angle of approximately 270°, when the supporting member takes up the position indicated by the broken lines in Figure 2.

Means may be provided for holding the supporting member in both the operative and inoperative or storage positions. In the operative position, lugs 9 which are integral with and preferably bent out from the arm 2a are shown secured to the wall or edge of the board by the wing screws 10. The wringer or supporting

member may be held in the storage position by any suitable form of catch.

Although the present invention has been described in connection with a specific embodiment, it will be apparent to those skilled in the art that modifications and variations may be made without departing from the fundamental concept disclosed herein. Such variations of construction as will be comprised within equivalent mechanism and that will accomplish practically what I have set forth are to be construed as within the scope of the following claims.

I claim:

1. A mounting for a domestic wash wringer comprising a bracket adapted to be secured to a supporting structure, a pivot pin mounted on said bracket, a wringer supporting member having a long arm and a short arm and being pivotally mounted on said pivot pin adjacent to the free end of said short arm, said long arm of the wringer supporting member being provided with means to engage and hold a wringer and adapted to move from an operative position at one side of the bracket to an inoperative position at the opposite side of the bracket, said short arm extending substantially parallel to the long arm on which the wringer is adapted to be mounted.

2. A mounting for a wash wringer adapted to be used in combination with a sink or the like comprising a bracket and a supporting member having two parallel arms rigidly connected by a third perpendicular arm, one of the parallel arms being adapted to be rigidly connected to the wringer and the other parallel arm being pivotable about a pin, which is held by the bracket and lies perpendicular to the three arms of the supporting member.

3. A mounting for a wash wringer adapted to be used in combination with a sink or the like comprising a bracket adapted to be secured below a sink or the like; a wringer supporting member having a relatively long arm adapted to be secured to a wash wringer, a relatively short arm generally parallel to said long arm, and a connecting arm between said long and short arms; and means pivotally securing said short arm to said bracket, whereby a wringer secured to said long arm may be swung from an operative position above the sink or the like to a storage position below the same.

4. A mounting for a wash wringer adapted to be used in combination with a sink or the like comprising an inverted channel bracket adapted to be secured below a sink or the like; a wringer supporting member having a relatively long arm adapted to be secured to a wash wringer, a relatively short arm generally parallel to said long arm, and a connecting arm between said long and short arms; and a pivot pin extending through the walls of said channel bracket and through said short arm, thereby pivotally securing said short arm to said bracket, whereby a wringer secured to said long arm may be swung from an operative position above the sink or the like to a storage position below the same.

5. A mounting for a domestic wash wringer according to claim 4, in which the pivot pin is located a distance below the surface of the sink which is greater than the length of the short arm, the long arm and the short arm extending in the same direction from the connecting arm.

ARTHUR HENRY FREEMAN.
